UNITED STATES PATENT OFFICE.

MORRIS MICHTOM, OF NEW YORK, N. Y.

DESIGN FOR A MUFF.

41,179.

Specification for Design.

Patented Feb. 14, 1911.

Application filed December 19, 1910. Serial No. 598,214. Term of patent 3½ years.

To all whom it may concern:

Be it known that I, MORRIS MICHTOM, a citizen of the United States, residing in the borough of Brooklyn, in the city of New York, county of Kings, and State of New York, have invented a new, original, and ornamental Design for a Muff, of which the following is a specification, reference being had to the accompanying drawing, forming part thereof.

is a side view in elevation of the muff, showing my new design.

I claim:

The ornamental design for a muff as shown.

Dated, New York, N. Y., December 15, 1910.

MORRIS MICHTOM.
